CLAIM

The ornamental design for a trash bin rack, as shown and described.

DESCRIPTION

FIG. 1 is a front, right and top perspective view of a trash bin rack showing my new design;
FIG. 2 is a rear, left and bottom perspective view thereof;
FIG. 3 is a front view thereof;
FIG. 4 is a rear view thereof;
FIG. 5 is a left side view thereof;
FIG. 6 is a right side view thereof;
FIG. 7 is a top plan view thereof;
FIG. 8 is a bottom plan view thereof;
FIG. 9 is an enlarged partial view of FIG. 1; and,
FIG. 10 is an enlarged partial view of FIG. 2.
The broken lines in the figures illustrate portions of the trash bin rack that form no part of the claimed design.
The dot-dash broken lines in the drawings depict enlarged portions that form no part of the claimed design.

1 Claim, 10 Drawing Sheets
